CLAIM

The ornamental design for a golf cart cargo box door, as shown and described.

DESCRIPTION

FIG. 1 is a front perspective view of the golf cart cargo box door showing my new design;

FIG. 2 is a rear perspective view thereof;

FIG. 3 is a cross sectional side view thereof, taken along the line 3-3 of FIG. 2;

FIG. 4 is a top plan view thereof;

FIG. 5 is a front elevation view thereof;

FIG. 6 is a bottom plan view thereof;

FIG. 7 is a rear elevation view thereof; and,

FIG. 8 is a right side view thereof.

The broken lines in the drawing depict portions of the golf cart cargo box door that form no part of the claimed design.
